CLAIM

We claim the ornamental design for a pliers stapler, as shown and described.

DESCRIPTION

FIG. 1 is a right side perspective view of a pliers stapler showing our new design;

FIG. 2 is a right side elevational view showing our new design;

FIG. 3 is a left side elevational view showing our new design;

FIG. 4 is a top plan view showing our new design;

FIG. 5 is a bottom plan view showing our new design;

FIG. 6 is a rear elevational view showing our new design; and,

FIG. 7 is a front elevational view of showing our new design.

The broken lines shown in FIG. 6 represent unclaimed portions of the pliers stapler and form no part of the claimed design.
